Filed Dec. 4, 1963, Ser. No. 77,668

Term of patent 14 years

(Cl. D4—3)

FIG. 5.

FIG. 6.

FIG. 7.

FIG. 8.

FIG. 9.

FIG. 10.

FIG. 1 is an isometric view of an embodiment of the partition mounted receptacle;

FIG. 2 is a front elevational view of the embodiment of FIG. 1;

FIG. 3 is a side elevational view of the embodiment of FIG. 1;

FIG. 4 is a top plan view of the embodiment of FIG. 1;

FIG. 5 is an isometric view of another embodiment of the partition mounted receptacle;

FIG. 6 is a front elevational view of the embodiment of FIG. 5;

FIG. 7 is a side elevational view of the embodiment of FIG. 5;

FIG. 8 is a top plan view of the embodiment of FIG. 5;

FIG. 9 is an isometric view of another embodiment of the partition mounted receptacle; and

FIG. 10 is a rear elevational view of the embodiment of FIG. 9.

The top plan view of the embodiment of FIG. 9 is identical with the view in FIG. 8 and the side elevational view is substantially identical with the side elevational

view shown in FIG. 7 with the exception that the inclined sides of the projecting portions of the receptacle taper inwardly in conformity with the isometric showing of FIG. 9.

I claim:

The ornamental design for a partition mounted receptacle, as shown and described.
